UNITED STATES PATENT OFFICE

106,453

DESIGN FOR AN INK ERASER

Rudolph George Roesch, Syracuse, N. Y., assignor to The Eraser Co., Inc., Syracuse, N. Y., a corporation of New York

Application August 12, 1937, Serial No. 71,051

Term of patent 7 years

To all whom it may concern:

Be it known that I, Rudolph George Roesch, a citizen of the United States of America, residing at Syracuse, in the county of Onondaga and State of New York, have invented a new, original, and ornamental Design for an Ink Eraser, of which the following is a specification, reference being had to the accompanying drawing forming part thereof in which:

Figure 1 is a perspective view of the ink eraser showing my design; Figure 2 is a side elevation of the same; Figure 3 is a front end view, and Figure 4 is a rear end view thereof.

I claim:

The ornamental design for an ink eraser, as shown.

RUDOLPH GEORGE ROESCH.
